UNITED STATES PATENT OFFICE.

WILLIAM F. POLSON, OF BUFFALO, NEW YORK.

CAN OPENER.

Application filed January 7, 1926. Serial No. 79,897.

My invention relates to improvements in can openers, and more particularly to that type in which a circular cutter is associated with a guide roller.

One of the objects of my invention is, to provide a can opener in which a circular cutter and a guide roller are carried by a single element, and means provided for relatively moving the two.

Another object of my invention is, to provide a can opener in which a supporting member is arranged to carry both the circular cutter and the guide roller and wherein an operating lever pivotally connected to said supporting member serves to impart movement to said circular cutter for moving the same toward or from said guide roller and for clamping a can between the two.

A further object is, to provide a can opener of simple construction, comparatively few parts and one in which maximum leverage is provided so that the device may be operated by a person comparatively weak in gripping power.

A still further object of my invention is to provide a can opener of the type mentioned in which relative movement of the cutting and guiding parts is attained by rectilinear movement of at least one of said parts.

With the above and other objects in view to appear hereinafter, my invention consists in the novel features of construction and in the arrangement and combination of parts to be hereinafter described and more particularly pointed out in the subjoined claims.

In the drawings:—

Fig. 1 is a side elevation of my improved can opener, showing the same in connection with a portion of a can illustrated in dotted lines.

Fig. 2 is a top plan view of the same.

Fig. 3 is a bottom plan view thereof.

Fig. 4 is an enlarged longitudinal section taken on line 4—4, Fig. 2, the same being shown in connection with the upper portion of a can and in the act of cutting the top of the can from the remainder of the same.

Fig. 5 is an enlarged transverse section taken on line 5—5, Fig. 4.

Fig. 6 is a detached perspective view of the cutter slide.

Fig. 7 is a longitudinal section taken on line 7—7, Fig. 4.

Reference being had to the drawings in

detail, the numeral 8 designates a can having a top or cover 9 secured to the upper end thereof by means of an over-hook seam or otherwise, forming an upstanding flange 10 around the upper end of the can and above the upper surface of the top or cover; cans of this kind being invariably provided with a depression 11 at the top.

My improved can opener, which in the embodiment shown is hand supported, comprises a support 12 formed of sheet material and stamped into substantially U-formation throughout its length; it, however, having a head or straight-lined portion 13 at one end and a curved handle portion 14 extending from the head or straight-lined portion to the other end thereof. The head or straight-lined portion has the sides 15 of its U-formation at right angles to the bottom 16 thereof, while the handle portion 14 has its sides merging into the bottom along curved lines.

At the junction of the handle 14 to the head 13, the sides of these parts are extended outwardly to form ears 17 and an operating lever 18 is disposed between the ears and pivotally connected thereto, a pivot 19 being passed through said operating lever and through said ears and being headed or upset at the outer sides of said ears, as at 20. The operating lever 18 is also formed of sheet material and in cross section is of U-formation. At its pivot-end, however, it is provided with an actuating tongue 21, the extremity of which is doubled upon itself, as at 22. The support 12 and operating lever 18 constitute the body of the device on which other parts of the device are supported, or to which other parts are connected.

Surrounding the pivot pin 19 are the convolutions of a trigger spring 23, the ends 24, 25 of said spring lying against the inner sides of the handle 14 and the operating lever 18, respectively; said spring, by reason of its being coiled around said pivot and having its end portions directed outwardly in diverging lines and in contact with said handle and said operating lever, tends to keep said lever distantly spaced from the handle 14, with the result that the actuating tongue 21 is swung to the extreme of its movement in one direction. Arranged within the head of the support is a cutter slide 26, which is of a width to have its edges bear slidably against the sides 15 of said head. Said cutter slide is provided

with a tapped opening 27 near one end thereof, and near its other end with two upwardly curved lips 28 rising above the upper surface of said slide and spaced apart to receive the rebent end 22 of the actuating tongue 21. The head of the support is provided in its bottom 16 with a longitudinal slot 29 over which the cutter slide is positioned.

30 designates a circular cutter having a cylindrical hub 31 serving as a pressure roller, the circular cutter 30 being in reality an outstanding flange on the roller having its edge beveled, as at 32, or otherwise fashioned to form a sharp cutting edge. This cutter is held in position on the head of the device by means of a screw 33, the shank of which is reduced at its inner end to form a shoulder 34, the reduced portion thereof being threaded and entered into the tapped opening 27 of the cutter slide 26, while the shoulder 34 thereof bears against the under or inner face of said slide. The enlarged portion of the shank of the screw extends through the elongated opening 29 in the head while the head of the screw, designated by the numeral 35, bears against the under side of the cutter. By reason of this screw being threaded into the cutter slide, it is non-rotatable and movable with the cutter slide, and the cutter is adapted for rotation on the shank of said screw.

36 designates a guide roller which has its peripheral edge roughened. I, however, preferably provide the peripheral edge with a circumferential groove 37 and the portions of said edge at opposite sides of the groove are knurled or otherwise roughened for a purpose to appear hereinafter. This guide roller is fastened onto an operating stem or shaft 38 having a reduced portion 39 fitting into an opening in the head of the support and a further reduced portion 40 is provided at the inner extremity of this shaft or stem, which is threaded and entered into a tapped opening formed axially in said guide roller. This guide roller is aligned with the hub or pressure portion 31 of the circular cutter and is rotated by the stem or shaft 38 which is provided at its outer end with a handle 41, preferably formed of a flat strip of metal having an opening 42 centrally between its ends, into which a portion of the metal forming the stem or shaft is forced to retain said handle thereon. This is accomplished by providing the stem or shaft with a slot 43, inserting the handle therein so as to conceal the opening 42 of said handle and then form a depression 44 on the exterior of said stem or shaft under pressure so as to force a stud-like portion 45 into said opening.

The cutter is normally spaced from the guide roller in the manner shown in Fig. 1, and with these parts in such position, the

operating lever 18 is in its outermost position, it being so maintained by the spring 23. The space between the circular cutter and the guide roller is sufficiently large to permit the flange 10 of a can to be easily passed between the two and upon depressing the operating lever 18 against the action of the spring 23, the tongue 21 at the inner end of said lever will force the cutter slide 26 lengthwise within the head, with the result that the cutting edge of the circular cutter is driven through the side of the can underneath the seam forming the flange 10, as clearly shown in Fig. 4. With the parts so disposed the handle 41 of the stem or shaft 38 is grasped and the stem or shaft rotated, with the result that the guide roller 36 is caused to rotate and its knurled or roughened peripheral edge to travel along the inner side of the flange.

The knurling or roughening of the guide roller causes rotation of the can and consequently rotation of the cutter loosely supported from the cutter slide, and by reason of the fact that the swinging movement of the operating handle or lever is converted to rectilinear movement and imparted to the circular cutter, greater freedom in action and a more positive cutting effect is secured than where the circular cutter depends on a swinging movement to enter and retain it in the wall of the can while the can rotates or the cutter rotates around the can.

Upon relieving the operating lever 18 of the hand pressure exerted, said lever is caused to return to its normal or outermost position, as shown in Fig. 1; and by reason of its positive connection with the cutter slide 26, said slide is also returned to normal position, with the result that the can opener is therefore one which is controlled with perfect freedom with one hand and conveniently operated with the other; this being due to the fact that the spring 23 makes it unnecessary to grasp the two handles of the device, by which is meant, the free end portion of the support and the free end portion of the operating lever, and causing them to move away from each other, which cannot otherwise be practically accomplished, except with the use of both hands, one applied to each handle; this being the common practice for releasing a can opener from a can among hand-supported can openers now in use, due to the fact that the rotatable cutter is invariably wedged into the wall of the can, remains hooked to some part of the can, or is frictionally retained in cutting condition.

The guide roller will last for a comparatively long period of time, and the cutter may be sharpened until the flanged portion thereof becomes worn to a point close to the hub 31, after which a new cutter can be easily placed in position by removing the

screw 33 and then removing the cutter and replacing it with another.

Having thus described my invention, what I claim is:—

5. 1. A can opener comprising a support having a straight-lined head and a curved handle portion, said support being formed of sheet material and being substantially of U-formation in cross section, a lever pivotally secured between the sides of said support and having an actuating tongue at its inner end, a spring for maintaining said lever in normal position, a cutter slide within said head having a pair of spaced lips 10 between which the actuating tongue of said lever is positioned, a circular cutter carried by said cutter slide, a guide roller carried by said head in spaced relation to said circular cutter, and a stem having a handle 15 and to which said guide roller is secured.
2. In a can opener, two pivotally connected members movable toward and from each other, one of said members being extended beyond the other to form a supporting head, two co-operating rotatable elements relatively movable and having their axes in planes parallel with the plane of movement of said pivotally connected members, one of said co-operating rotatable 25 elements being operatively connected with one of said pivotally-connected members so that it is moved relatively toward and from the other rotatable member upon corresponding movements of said last-mentioned 30 pivotally-connected member.
3. A can opener, comprising two pivotally-connected members movable relatively in a vertical plane, two rotatable elements adapted to co-act for cutting operation and

carried by at least one of said pivotally-connected members to move relatively in a horizontal plane upon relative movement of said pivotally-connected members, and means for rotating at least one of said rotatable elements.

4. A can opener comprising a support, two rotatable elements carried by said support and relatively movable in a horizontal plane, one of said elements being a cutter and the other a guide roller, an operating lever pivoted to said support for movement in a vertical plane and having operative connection with one of said rotatable elements, and means for rotating one of said rotatable elements.

5. A can opener comprising a body having two relatively movable co-operating members pivotally connected together and each having a handle, two rotatable elements co-acting to cut through a wall of a can and supported by said body, one of said elements being a cutter movable in a horizontal plane from inoperative to operative position and reversely, and at least one of said two co-operating members being movable in a vertical plane from inoperative to operative position and reversely, the relative movements of said co-operating members and the movement of said cutter from inoperative to operative positions being effected by manual effort, a spring to cause relative movement of said co-operating members and movement of said cutter from operative to inoperative positions, and means to rotate one of said rotatable elements.

In testimony whereof I affix my signature.
WILLIAM F. POLSON.
